UNITED STATES PATENT OFFICE

HENRY W. LYON, OF ERIE, PENNSYLVANIA, ASSIGNOR TO GENERAL ELECTRIC COMPANY, A CORPORATION OF NEW YORK

ELECTRIC SWITCH

Application filed November 5, 1927. Serial No. 231,359.

This invention relates to electric switches, particularly of the knife blade type, and has for its principal object the provision of an improved knife blade switch particularly 5 adapted for heavy current duty and also suitable for dead front switchboard mounting. However, the simplified and relatively inexpensive construction of the improved switch of the present invention renders it ad- 10 vantageous for a wide field of application.

With a knife blade switch of large current carrying capacity, a relatively large force is required to open and close the switch due to the heavy frictional engagement of the switch 15 blade with the cooperating contacts. Also where the knife blade switch is to be used in a switchboard of the dead front type, the necessity for effectively insulating the operating mechanism from the switch blades arises. 20 These difficulties are effectively overcome by the present invention in a relatively simple and inexpensive manner.

Briefly, in accordance with the preferred form of the present invention, the blades of 25 the switch are sector shaped copper plates pivoted at the apex of the sector with gear teeth cut in the periphery of the sector blades. The operating mechanism for the switch includes a small pinion gear preferably of insulating material, adapted to mesh with the teeth on the periphery of the sector shaped switch blades. Thus rotation of the small pinion gear provides a powerful operating 30 force for opening and closing the switch. In addition, with the gear formed of insulating material the operating mechanism is effectively insulated from the switch blades. This improved construction also readily permits any desired number of switches to be located 35 one behind the other and operated by means of a common shaft provided with an operating gear pinion for each switch.

The accompanying drawing illustrates a 40 preferred form of switch embodying the invention. Fig. 1 is a perspective view of a three pole, double throw switch for heavy duty service and dead front switchboard panel mounting. Fig. 2 is a front view of the switch with the switchboard panel removed 45 to more clearly reveal the arrangement of the

sector switch blades, the cooperating fixed contacts and the operating pinion. Fig. 3 is a side view of the switch shown in Fig. 1.

As shown in Fig. 1, the improved switch 55 comprises the three movable blades 10, 11, 12, which upon rotation of the shaft 13 by means of the operating hand wheel 14 are operated through the agency of the gear pinions 15, 16, 17, meshing with the teeth provided on the periphery of the corresponding switch 60 blades. In the preferred form shown each of the switch blades 10, 11, 12, is composed of two sector shaped copper plates spaced apart sufficiently to engage snugly with the co- 65 operating stationary contacts as indicated in Fig. 3.

As more clearly shown in Fig. 2, the sector 70 switch blade 10 is pivotally mounted at its apex upon the contact lug 18 secured to the base 19 with the two plates of the blade firmly 75 pressed into good current conducting contact with the lug by means of the bolt 20 and the spring washers 21. The switch blade 10 is operable into engagement with either of the cooperating stationary contacts 22 and 23 mounted on the base 19. The spacing of the 80 two plates forming the switch blade 10 is such that the stationary contacts are engaged therebetween with a good current-conducting contact. The springs 24 serve to maintain the two blades in engagement with the contacts. Suitable conductor cable connections are made to the stationary contacts 22 and 23 and also the lug 18, as indicated in Fig. 2. The switch blades 11 and 12 are each mounted 85 at their apex upon a lug corresponding to the lug 18 and cooperate with stationary contacts corresponding to the contacts 22 and 23 except that the blade 11 had only one elongated stationary contact 23'.

As indicated in Fig. 1, the base 19 with the 90 movable switch blades and the stationary contacts thereon is mounted behind the switchboard panel 25 through which the end 95 of the operating shaft 13 extends to receive the operating hand wheel 14. The other end of the shaft 13 is mounted in a suitable bearing 26 supported on the frame work 27 to which the base 19 is secured.

The operation of the switch will be obvious 100

from the foregoing description. Upon rotation of the hand wheel 14 the pinion gears 15, 16, 17, carried by the shaft 13 in mesh with the teeth formed on the periphery of the sector shaped switch blades serve to rotate the blades into and out of engagement with the stationary contacts cooperating therewith.

Only a relatively small force is required to rotate the hand wheel 14 even though the switch blades are in firm frictional engagement with the stationary contacts and the pivot lugs. This is due to the mechanical leverage provided by the small pinions meshing with the teeth on the edge of the switch blade. It will be evident that simply by extending the base 19 and the shaft 13 additional switch blades and operating pinions therefor may be added as desired. Due to the insulating characteristics of the operating pinions 15, 16, 17, the operating shaft and the hand wheel 14 are effectively insulated from the switch blades and the switch blades are insulated from each other.

What I claim as new and desire to secure by Letters Patent of the United States is:

1. An electric switch comprising cooperating relatively movable current conducting members, one of said members having gear teeth formed therein, and operating means for effecting relative movement of the members including a toothed gear element in mesh with the teeth formed in said one movable current conducting member.

2. In an electric switch, the combination of a rotatably mounted switch element having an arcuate periphery, and rotatable means in engagement with the periphery of the member for operating the same.

3. In an electric switch, the combination of a switch blade of sector shape rotatably mounted at the apex, and rotatable means engaging with the periphery of the blade for operating the same.

4. An electric switch comprising a movable switch element having a toothed periphery, a stationary switch element cooperating therewith, and means for operating the rotatable element into and out of engagement with the stationary element comprising a gear pinion disposed in mesh with the teeth in the periphery of said switch element.

5. An electric switch comprising a pair of sector shaped blades disposed in parallel spaced alignment and rotatably supported at the apex, a stationary contact disposed to be engaged between said blades, and means for operating the blades comprising a rotatable member engaging with the periphery thereof.

6. An electric switch comprising a plurality of sector shaped switch blades rotatably mounted at their apexes in spaced alignment and having gear teeth formed in the periphery thereof, a common operating shaft

therefor, and gears of insulating material mounted on the shaft in mesh with the teeth on the periphery of the said blades.

7. An electric switch comprising a plurality of pairs of sector shaped switch blades, the blades in each pair being spaced apart and having gear teeth formed in the periphery thereof, said pairs of blades being mounted at their apexes in spaced alignment, a plurality of stationary contacts, each disposed to be engaged between a corresponding pair of blades, and a common operating shaft having gear elements of insulating material in mesh with the teeth formed on the periphery of said pairs of blades for operating the same into and out of engagement with the cooperating stationary contact.

In witness whereof, I have hereunto set my hand this 3rd day of November, 1927.
